CIRCUIT BREAKING PLUG

Harry Weiner, Chicago, Ill., assignor to Florio G. Flosi, doing business as Allied Industries, Chicago, Ill.

Application October 26, 1942, Serial No. 463,337

5 Claims. (Cl. 200—113)

This invention relates to that type of electric circuit breaking plugs which, when the circuit is overloaded, or when a "short" is produced, will break the circuit and will return again to close the circuit when the latter is relieved of the load or the "short."

One of the objects of the invention is to provide a simple and effective plug of this character, which will instantly break or interrupt the circuit when an overload is produced.

A further object is to provide in an improved plug of this character, two contact members or elements which, before the plug is ready for use, or before it is inserted into the wall socket or line, are normally in contact, but separate from each other, and which, when a current of predetermined strength is passed through the contacts, will fuse together, and they will remain in this condition, with the current flowing therethrough, until the circuit is subjected to an overload, or a "short" is established. The passing of the current through the normally separate contacts will cause the contacts to fuse together, by forming a "teat."

The establishment of an overload or "short," after such fusing, will heat the contacts to a degree to melt the fused point, whereupon the electrodynamic principle involved will, when the metal at the fused point is soft, force the flow of the current in an abnormal manner and cause it to act as a striking force at the point of least mechanical resistance, which is the fused point, causing the contacts to separate and open the circuit.

Shortly thereafter, and when the material in one of the contacts cools, the residual magnetism in the other contact and the inherent resilient properties of the first mentioned contact, will cause the contacts to again assume engagement. This action takes place so rapidly that the metal in one of the contacts will still be soft enough to cause the contacts to fuse together, forming the "teat," which latter will be commensurate in size with the amount of the resistance caused by the appliance or attachment with which the circuit is employed. That is, the size of the "teat" or fused point between the contacts will be controlled by the strength of the current employed.

Each time that the contacts are brought back into engagement, after being separated, a fused point will be established, and a completely closed circuit will also be established through the plug.

Any suitable material which will accomplish the desired result may be employed, but it has been found in practice that when one of the con-

tacts is constructed of cold rolled steel and the other of cold rolled bi-metallic steel, they will operate effectively, one of the contacts being softer than the other, and the said other contact, being not only harder, but much thinner, will result in the establishment of a fusion of the two at the point where they contact.

Such a plug will operate automatically and will last for a considerable length of time, and for a great number of separations and fusions together, according to the size, thickness and quality of the materials used.

To the attainment of these ends and the accomplishment of other new and useful objects as will appear, the invention consists in the features of novelty in substantially the construction, combination and arrangement of the several parts, hereinafter more fully described and claimed and shown in the accompanying drawing illustrating this invention, and in which:

Fig. 1 is a top plan view of a plug of this character, constructed in accordance with the principles of this invention.

Fig. 2 is a vertical sectional view taken on line 2—2, Fig. 1.

Fig. 3 is a vertical sectional view taken on line 3—3, Fig. 1, showing the plug in condition for use.

Fig. 4 is a detail perspective view of one of the contact members.

Fig. 5 is a detail perspective view of the other contact member.

Fig. 6 is a view, similar to Fig. 3, of a modified form of the invention.

Referring more particularly to the drawing, the numeral 10 designates, generally, a casing constructed of any suitable non-conducting material, and in which casing is provided a chamber 11 open at the upper end. The chamber is adapted to be closed in any suitable manner, such as by means of a transparent closure 12 seated within a recess 13.

The numeral 14 designates, generally, a contact member which is constructed of any suitable material, preferably cold rolled steel, and is bent or shaped to form a contact edge 15. This contact member 14 is seated in a recess 16 in the wall of the chamber 11, and is held in position in any suitable manner, such as by means of a contact terminal 17 which passes through the wall of the housing or casing 10 and is secured to the contact 14 by one end entering an opening 18 in the contact, and with the end or extremity of the terminal upset, as at 19.

Within the chamber 11 is arranged another contact member 20 which is constructed of any

suitable material, either bi-metal or cold rolled steel, and is considerably harder than the contact 14, and much thinner. This contact member is provided, preferably, with a deflected base portion 21, by means of which it may be secured within the chamber 11, preferably by means of a terminal 22 passing from the outside of the chamber thereinto, and with the extremity 23 upset. The opening 24 in the base 21 is of a considerable diameter, so as to provide narrow portions 25 on each side of the opening.

Normally, when the contact member 20 is secured in position, its inherent resiliency will cause it to engage the edge 15 of the contact 14, but will be separate therefrom. When a current of predetermined strength is passed through the plug, the material from which the contact 14 is formed will become soft and the contact member 20 will be fused thereto. This fusion will remain intact so long as a normal current of predetermined strength passes through the plug. When, however, an abnormal current is passed through the plug, the point of fusion will melt and the contact 20 will be disconnected from the contact 14. The action is that, when an abnormal current flows through the plug, the tendency is to "kick" the contact 20 away from the contact 14, and this electrodynamic action will cause the contact member 20 to move from the position shown in solid lines to the position shown in dotted lines, in Fig. 3, thereby interrupting the current. As soon as the line is reduced to a normal current, the residual magnetism in the contact 14, together with the inherent resiliency of the contact 20, will cause the latter to be moved back into engagement with the contact 14, as shown in full lines in Fig. 3. The contact 14 being soft, and the contact 20 being much harder, these two contacts will again fuse together at the point of engagement. This action will be repeated until the contact member 20 wears away by being burned out. The opening 24 being of a considerable diameter with respect to the base 21, forming the narrow portions 25, serves as an additional means for interrupting the current, as these points, under an abnormal load, will burn out.

In the form of the invention shown in Fig. 6, there is provided a manual means for moving the contact member 20 back into engagement with the contact 14, so as to permit the two contacts to become fused together. Any suitable means may be provided for that purpose, but a simple and efficient means embodies a shaft 26 having an arm 27 and a handle 28, the shaft 26 and arm 27 being disposed within the chamber 11, and the handle 28 being disposed in a position whereby it is accessible from the outside of the casing.

While the preferred form of the invention has been herein shown and described, it is to be understood that various changes may be made in the details of construction and in the combination and arrangement of the several parts, within the scope of the claims, without departing from the spirit of this invention.

What is claimed as new is:

1. A circuit breaking plug embodying a casing of non-conducting material having an open end, two contact members within the casing normally separate from each other, but having a point contact engagement, contact terminals individual to said members and extending to the outside of the casing, the composition of said contact members being such that when a normal current

- is initially passed through said members they will fuse together at said point of contact, and when said members, after they are fused together, are subjected to an abnormal current, the point of fusion will soften and one of said contact members will be forced away from the other contact member to interrupt the circuit, the residual magnetism in one of said contact members after the separation of the members, and the inherent resiliency in the other contact member operating, when said abnormality is relieved, to cause the contact members to be brought into engagement, said members then again becoming fused together.
15. 2. A circuit breaking plug embodying a casing of non-conducting material having an open end, two contact members within the casing normally separate from each other, but having a point contact engagement, contact terminals individual to said members and extending to the outside of the casing, the composition of said contact members being such that when a normal current is initially passed through said members they will fuse together at said point of contact, and when said members, after they are fused together, are subjected to an abnormal current, the point of fusion will soften and one of said contact members will be forced away from the other contact member to interrupt the circuit, the residual magnetism in one of said contact members after the separation of the members, and the inherent resiliency in the other contact member operating, when said abnormality is relieved, to cause the contact members to be brought into engagement, said members then again becoming fused together.
20. 25. 30. 35. 40. 45. 50. 55. 60. 65. 70. 75. 4. A circuit breaking plug embodying a casing of non-conducting material, two contact members within the casing normally separate from each other, but having a point contact engagement, contact terminals individual to the said members and leading to the outside of the casing, the composition of said contact members being such that when a normal current is initially passed through said members they will fuse together at said point of contact, and when said members, after they are fused together, are subjected to an abnormal current, the point of fusion will soften and one of said contact members will be forced away from the other contact member to interrupt the circuit, and means for positively moving one of the contact members into engagement with the other contact member when they are separated, whereby they may be fused together.
4. A circuit breaking plug embodying a casing of non-conducting material, two contact members within the casing normally separate from each other, but having a point contact engagement, contact terminals individual to the said members and leading to the outside of the casing, the composition of said contact members being such that when a normal current is initially passed through said members they will fuse together at said point of contact, and when said members, after they are fused together, are subjected to an abnormal current, the point of fusion will soften and one of said contact members will be forced away from the other contact member to interrupt the circuit, and means separate from said contacts and accessible from the outside of said casing for positively causing

the separated contact members to engage, whereby they may be fused together.

5. A circuit breaker embodying a support, two contact members mounted thereupon, normally separate from each other, but having a point contact engagement, contact terminals individual to said members, the composition of said contact members being such that when a normal current is initially passed through said members they will fuse together at said point of contact, and when said members, after they are fused together, are subjected to an abnormal current,

the point of fusion will soften and one of said contact members will be forced away from the other contact member to interrupt the circuit, the residual magnetism in one of said contact members after the separation of the members, and the inherent resiliency in the other contact member operating, when said abnormality is relieved, to cause the contact members to be brought into engagement, said members then 10 again becoming fused together.

HARRY WEINER.
